UNITED STATES PATENT OFFICE.

JAMES KEISTER, OF STEUBENVILLE, OHIO.

INTERNAL-COMBUSTION ENGINE.

1,167,055.

Specification of Letters Patent. Patented Jan. 11, 1916.

Application filed May 28, 1912, Serial No. 700,160. Renewed August 6, 1915. Serial No. 42,981.

To all whom it may concern:

Be it known that I, JAMES KEISTER, a citizen of the United States, and a resident of Steubenville, in the county of Jefferson and State of Ohio, have invented a new and Improved Internal-Combustion Engine, of which the following is a full, clear, and exact description.

My invention relates to internal combustion engines, especially of the type designed for use on motor vehicles, and it includes improved valve mechanism and operating connections therefor by means of which ordinary valves of the puppet type are dispensed with.

The primary object of my invention is to secure the proper operation of the valves throughout the cycle of the engine, and the proper lubrication to reduce the resistance of the working parts, and in general to improve the construction of an engine of this type.

I attain the above objects by means of a casing in which a pair of sleeve valves are mounted to reciprocate, these sleeve valves having ports therein which register in proper order with the inlet and outlet ports of the engine and are connected by suitable means to be operated from the crank shaft in the manner required. These valves are so fitted as to inclose the power chamber, and between them and the main walls of the engine is a space through which a cooling medium, preferably oil, is made to circulate.

Reference is to be had to the accompanying drawings forming a part of this specification, in which the same characters of reference indicate the same parts in all the views.

Figure 1 is a vertical longitudinal section through one cylinder of an engine made in accordance with my invention; Fig. 2 is a vertical longitudinal sectional view of an engine of the four-cylinder type made in accordance with my invention; Fig. 3 indicates a set of diagrammatic views showing the various steps in the operation of the valve construction; and Fig. 4 is a diagrammatic view showing the relative location of the cranks by means of which the valve sleeves of the four cylinders are operated.

On the drawings, the numeral 1 indicates a crank case, which, as shown in Fig. 2, is provided with a pair of openings in its top, and mounted upon this top and surrounding

these openings is a pair of casings 2, in each of which is formed a pair of power chambers in a manner hereinafter to be fully set forth.

My invention is provided with the usual crank shaft 3, on which are formed cranks 4, and these cranks 4 are connected by means of rods 5 with pistons 6, these pistons serving to draw in a combustible charge and compress the same when it is to be ignited in the usual way.

The top of each casing 2 is provided with a pair of openings in axial alignment with the pistons 6, and these openings are closed by heads 7, each of which has an inward-extending projection 8 connected to an integral flange 9 extending back toward the head 7, as shown plainly on the drawings. In the outer face of the flanges 9 are embedded a plurality of packing rings 10, and these packing rings serve to provide a snug fit between the heads on the casings and the valve sleeves which are mounted in each casing to coöperate with the pistons in forming the working or power chambers of my engine. Each head 7 is provided with the usual openings 11 to receive the igniters and the priming cups.

Carried inside of each of the casings 2 is a pair of integral rings 12, each of which surrounds one of the projections 8 supported by the head 7, but these rings are located slightly below the projections 8 and the flanges 9 thereon, so that the lower side of these rings will be below the lower end of the projection 8, as shown. The rings in each casing are separated from each other and from the casing, except at diametrically opposite points, where they are connected by means of webs, as shown in Fig. 1, to the outer casing wall. Through these rings and through the walls of the casings 2 lead passages 13 and opposite passages 14. The passages 13 are two in number and are arranged on one side of each casing 2, and the passages 14 are likewise two in number and are arranged on the opposite side of each casing 2; and each passage 14 will be directly opposite one of the passages 13. These passages 13 and 14 constitute means for admitting gaseous fuel to the engine and conducting the same therefrom; and each of the passages 13 and 14 is of course arranged in such position that it will coöperate with one of the pistons 6, as will be readily understood.

105

110

The passages 13 and 14 for each ring of course pass through the webs which connect this ring to the casing 2, as Fig. 1 shows.

The internal diameter of the rings 12 is 6 slightly greater than the external diameter of each flange 9, leaving an annular space between the overlapping portions of these two parts. The rings 12 are provided with packing rings 15, and in the space between 10 each ring 12 and each flange 9 reciprocate the ends of a pair of valve sleeves shown at 16 and 17, the latter telescoping within the former. The piston 6 is of such diameter that it will fit readily within the valve sleeve 17, and each projection 8 forms with these valve sleeves 16 and 17 and the piston 6 which reciprocates within the latter, an explosion chamber in which the fuel is ignited to impart power to the piston 6 when the 20 engine is used.

Between the valve sleeve 16 and the walls of the casing 2 is a space 18 which communicates with a similar space 19 in the head 7. This space 19 is extended down between the 25 inner wall of the head 8 and the flange 9 and serves as a cooling chamber through which oil is circulated. Near the upper ends of the sleeves 16 and 17 are formed ports which coöperate with the inlet and exhaust 30 ports 13 and 14. The outer sleeve 16 has ports 19, being located on opposite sides of the sleeve, but out of transverse alinement with each other. The inner sleeve has ports 20 also on opposite sides, but in transverse 35 alinement with each other; and when the ports 19 and 20 on one side register with the port in the wall of the casing 2 on that side, the operation of admission or exhaust can take place.

40 The space 18 is closed at the bottom by means of a web which separates the interior of each casing 2 from the interior of the crank case 1. The web for each of the casings 2 has apertures through the same large 45 enough to receive the outer sleeve 16, and these apertures are surrounded by upward-extending flanges 21 in which are formed spaces to receive packing rings 22 which engage the outer surface of the sleeve 16 and 50 make a tight fit. Thus, any oil passing into the space 18 is prevented from dripping into the crank chamber, and the oil not only serves to cool the engine but it also serves to lubricate the sleeves 16 and 17, since it comes 55 in contact with the outer face of the sleeve 16 and the upper ends of both sleeves, so that when these sleeves are in motion the oil is gradually distributed over their entire surface, and all of the friction of the sleeves 60 upon each other and upon the flanges 9, the rings 12 and 21 and the piston in the inner sleeve, is practically eliminated.

As will be observed, the web from which the flanges 21 project into the cylinder is 65 located above the lower end of each casing 2.

This is because the lubricating and cooling chamber does not have to extend any farther down than the position occupied by the inner end of the piston at the end of its out stroke, and the space between this web and the top 70 of the crank casing affords room for the reciprocation of the sleeves and the connections by which they are operated.

At the lower ends of each of the sleeves 16 and 17 is formed an annular groove 23 by means of annular ribs, and these grooves serve as means for connecting to the valve sleeves a pair of operating rods 24 and 25, these operating rods being two for each power chamber, and the former being connected to the inner sleeve and the latter to the outer one. The ribs formed by the sides of the grooves 23 support lugs, as shown in Fig. 1, which lugs are of course perforated 80 to receive pins passing through the upper ends of the rods 24 and 25, so as to connect these rods in a pivotal way to the sleeves. At the lower end of the rod 24 is pivotally-connected a slotted link 27, and at the lower end of the rod 25 is pivotally connected a similar slotted link 28. These slotted links are 85 mounted to slide and rock upon a longitudinal bar 29 mounted in the crank casing 1, and parallel with the crank shaft; and the links 27 and 28 are connected by means of rigid rods 30 and 31, respectively, to cranks on an operating shaft 32. This operating shaft 32 is also parallel with the crank shaft 3 and carried in bearings in the crank casing 1, and is operated from the crank shaft at 90 half the speed thereof by means of a sprocket chain, as Fig. 1 illustrates.

The bar 29 may be provided with collars, as shown in Fig. 2, on each side of each link 27 and 28 to prevent lateral movement of these links along the bar. In this way the links will always be kept in proper position.

The mode of operation of my engine is as follows: The order of ignition in the four cylinders is first, third, fourth and second, as is usual in four-cylinder motors of the four-cycle type; and it will be observed that as the crank shaft 3 rotates it causes the shaft 32 to rotate in the same direction, owing to the chain and sprocket connection 110 mentioned. As the shaft 32 rotates it operates the rods 30 and 31, and through these rods the links 27 and 28 are moved to actuate the rods 24 and 25 and reciprocate the sleeves 16 and 17 to open the ports 13 and 14 to admit and discharge gas, and close 115 these ports during the operations of compressing and igniting the fuel in the usual way.

Reference is now had to Fig. 3, which 125 shows in outline the positions of the various parts at a number of points in the complete cycle of operation of one cylinder, the mode of operation being the same for the other cylinders, as will be readily understood.

Referring to diagram A, it will be seen that the main crank 4 is in such position that the piston 6 is at the end of its out stroke, and the cranks connected to the rods 30 and 31 on the shaft 32 are in such positions that the ports 19 and 20 are out of registry with the port 14; while the port 19 on the opposite side is in registry with the port 13, but there is no communication with the inlet port 13 at this time, because the other port 20 is out of registry not only with the port 13, but with the adjacent port 19 as well. Compression is now about to be effected.

15 The position of the parts on diagram B shows the piston at the mid point of its in stroke, the crank 4 having rotated 90° and the other cranks 45° each. As a result, both the rods 30 and 31 have been drawn to the left to some extent, and it will be seen that the link 27 has been moved substantially without being rocked around the shaft 29 at this time; but owing to the curvature of the slot therein, which extends first downward 20 to the right and then substantially horizontal, and then downward again at the right end of the slot, the rod 24 has been pushed upward a certain distance, moving the sleeve 17 with it. This causes the ports 25 20 to be moved still farther toward the head 7 and away from the ports 13 and 14. The other link 28, whose slot is curved somewhat different from the slot in the link 27, that is to say, first horizontally to the right, and 30 then downward, and then horizontally to the right again, has not only been raised as it slides along the bar 29, but rocked to some extent also in a counter-clockwise direction. As a result, the rod 25 is moved 35 upward and the sleeve 16 is raised so that its port 19 on the left side is brought partly into registry with the port 14, while its port 19 at the right is carried wholly out of registry with the port 13. The compression 40 chamber thus remains closed. When the crank 4 rotates 90° farther, and the cranks connected to the rods 30 and 31 45° farther, the position of the parts will be as shown in diagram C. The rod 30 is rocked to some 45 extent at this time around the bar 29, but with very little effect so far as moving the sleeve 17 is concerned. The other rod 31 is moved substantially lengthwise, but the slot in the link 28 attached thereto has a 50 cam action on the bar 29, moving the rod 25 upward, and with it the sleeve 16, until the port 19 at the left is a little bit beyond registering position with respect to the exhaust port 14. The piston is now at the 55 inner end of its stroke, with the power chamber all closed; and explosion can take place.

I now refer to the four lower diagrams E, F, G and D, passing from left to right. In these diagrams the link 27 and the rod

30 are shown in full lines instead of in dotted lines, as in the four upper diagrams, and the link 28 and the rod 31 are shown in broken lines instead of full lines, as in the four upper diagrams, three of which have 70 already been described. This method of illustration has been followed for the sake of showing each of the links 27 and 28 and the rods 30 and 31 in full lines somewhere, and as it is not possible to show them both 75 in full lines on each of the diagrams, the illustration will be made clearer by the method in question: namely, delineating each in full lines on part of the diagrams and in broken lines on the remaining dia- 80 grams.

After the explosion has taken place and the piston 6 has moved outward to some extent, the position of the rods 30 and 31 will be as shown in diagram D. The rods 30 85 and 31 are now as far to the left as they can go, and the bar 29 is at the extreme right end of the slots in both the links 27 and 28, and the ports 19 and 20 are not in any position to open the power chamber to the ex- 90 haust port 14 to permit the operation of exhausting to begin. This takes place be- 95 cause, in moving from the position shown in C to those shown in D, the link 27 is rocked upward to some extent, but there is hardly any movement transmitted to the sleeve 17 at this time; while the movement of the rod 31, which rocks the link 28 upward, and therefore swings the lower end of the rod 25 outward, lowers the sleeve 16 a 100 little, until the port 19 at the left comes into full registry with the exhaust port 14. When the piston has reached the end of its out stroke the rod 31 will be in the position shown in diagram E, with the bar 29 still 105 in the extreme right of the slot in the link 28, and the bar 30 will have moved to the right, rocking the link 27 to some extent and at the same time causing it to move downward, owing to the direction in which the 110 slot therein extends, pulling down on the inner sleeve 17. Both ports at the left are now in registry with the exhaust port 14, while the inlet port 13 remains closed, and the outflow of inert gases of combustion be- 115 gins. The outer sleeve 16 remains substan- 120 tially stationary at this time. The further movement of the piston causes the rods 30 and 31 to assume the position shown in dia- 125 gram F, the link 28 still having the bar at the right end of the slot therein and the link 27 having been moved farther to the right along the bar, with the result that practi- 130 cally no movement of the sleeves is effected. This permits the sleeves to remain station- 135 ary and the ports 19 and 20 in registry with the ports 14 at this time. To effect ignition, the shaft 32 next forces the rods 30 and 31 to move farther to the right, rocking the rod 31 upward and the other rod 30 downward,

and causing the link 28 to move its right end away from the bar 29, and the link 27 to move its left end against the bar 29. The sleeve 17 as a result has hardly moved at 5 all, but the sleeve 16 has moved to a sufficient extent to put the port 19 in the left side out of registry with the adjacent port 20 on the inner sleeve, the other port 20 remaining practically in alignment with the 10 port 18. This port 18 is now opened through the adjacent port 19 on the right-hand side of the sleeve 16 coming partly into registry therewith, and the supply of mixture to the power cylinder begins. The full 15 open position of the inlet is shown in diagram H, wherein the crank on the shaft 32 moves the rod 30 and the link 27 without causing perceptible relative movement of the inner sleeve 17 while the rod 31 is moved 20 to carry the link 28 still farther to the right, lowering this link and pulling down on the rod 24 and down on the sleeve 16, until the ports 19 and 20 adjacent the inlet port 18 open this port fully. 25 The above motions are repeated for every cycle in the operation of the various cylinders of the engine, and these motions are of course the same for each cylinder as the engine continues running.

30 Fig. 4 illustrates the relative positions of the cranks by means of which the rods 30 and 31 connect the links 27 and 28 of each cylinder to the operating shaft 32. The cranks for each cylinder are arranged 70° apart. The position of the cranks for the first cylinder are indicated by the numerals 1^a and 1^b, the former leading. Those for the cranks of the second cylinder are indicated by the numerals 2^a and 2^b; those for the cranks of the third cylinder by 3^a and 3^b, and those for the cranks of the fourth cylinder by 4^a and 4^b. It will be observed that the crank positions for each cylinder are about 70° apart, the advance crank for cylinder 1 leading the advance crank for the third cylinder by 90° and the advance crank for the fourth cylinder by 180° , and the advance crank for the second cylinder by 270° ; and by comparing the crank positions for the first cylinder on Fig. 4 with diagram E on Fig. 3, it will be seen that the first cylinder is exhausting while the cranks for the third cylinder occupy the position shown in diagram C, for ignition. Further, 45 the crank positions for the fourth cylinder, whose piston is compressing at this time, are much the same as the positions illustrated in diagram A, and the crank positions for the second cylinder, which is sucking in 50 a charge, are substantially the same as those illustrated in diagram G. In all these cases the pistons are supposed to be beginning the strokes referred to, and the relative positions of the pistons in the four cylinders are 55 shown in Fig. 1, wherein the first piston is 60

in position to start the exhaust; the second piston about to start suction; the third piston about to begin its power stroke; and the fourth piston about to start compressing.

From the above description it will be apparent that I secure an engine which is perfectly noiseless in operation and the parts are efficiently cooled, and the oil in the cooling chamber not only carries off the heat to the extent required, but serves for the purpose of efficiently lubricating all the parts. I wish to have it understood further that I do not care to be limited to the exact details of construction shown and described in the foregoing, but reserve to myself the right to make such changes in the shape, size and arrangement of the parts as fairly fall within the scope and spirit of my invention.

Having thus described my invention, I claim as new and desire to secure by Letters Patent:

1. In an internal combustion engine, the combination of a crank case, a casing mounted thereon, a head for said casing having a projection extending into the casing and provided with a return flange, a valve sleeve inside of said casing and reciprocating at the outer side of the said flange of the head, and a piston reciprocating in said valve sleeve, the said valve sleeve forming with the piston and the projection of the head a power chamber, the valve sleeve being spaced from the outer wall of the casing and the interior of the casing head communicating with said space to permit of the circulation of a cooling agent.

2. In an internal combustion engine, the combination of a casing, a ring carried inside of the same, said ring having inlet and outlet ports therein and opening through the wall of the casing, a valve sleeve having telescoping engagement with said ring and having corresponding ports formed therein to register with the first-named ports, a piston reciprocating in said sleeve, and a head carried by the casing and having a projection which extends into the valve sleeve, said projection being of less diameter than the ring and surrounded at its inner end by the latter, the projection forming with the piston and valve sleeve a power chamber.

3. In an internal combustion engine, the combination of a casing having a head, said head having a projection with a returned flange thereon, a ring supported by said casing and surrounding the lower part of said flange but separated therefrom by means of an annular space, said ring having ports therein extending therethrough and through the wall of the casing, a valve sleeve located within said casing and reciprocating through the space between said ring and flange, and a piston reciprocating in the valve sleeve forming therewith and with the head a power chamber.

4. In an internal combustion engine, the combination of a casing, a head for said casing having a projection extending into the same, said casing having a returned flange forming a space between the same and the adjacent wall of said projection, a ring supported by said casing surrounding the lower part of the flange but separated therefrom by an annular space, said ring having ports extending therethrough and through the wall of the casing, a valve sleeve reciprocating at one end in the space between the projection and the ring, a piston reciprocating in said valve sleeve and forming therewith and with said head a power chamber, said valve sleeve being separated from the outer wall of the cylinder by a space communicating with the interior of the head to permit the circulation of a cooling and lubricating agent in contact with the outer surface of the valve sleeve and the inner end thereof.
5. In an internal combustion engine, the combination of a casing, a pair of heads for closing the same, each of said heads having an internal projection with a returned flange thereon separated from the outer wall of the projection, a pair of rings supported by said casing, each of said rings surrounding one of said projections at its inner end but separated therefrom by an annular space, each of said rings having ports passing therethrough and the outer wall of the casing, a valve sleeve received in each space between the ring and the projection and having ports therein to register with the first-named ports, a piston within each of said valve sleeves and forming therewith and with the heads a power chamber, and a web closing the opposite end of the casing and having openings therethrough to receive the valve sleeves, said valve sleeves being spaced from the walls of the casing to form a space communicating with spaces in the heads to permit circulation of a cooling and lubricating agent in contact with the lateral surfaces and the inner ends of the valve sleeves.
6. In an internal combustion engine, the combination of a reciprocating valve sleeve, a piston moving within the same, an actuating rod connected to said valve sleeve, a slotted link connected to the said rod, a second rod connected to said link, and a crank for operating the same.
7. In an internal combustion engine, the combination of a pair of reciprocating valve sleeves, a piston moving in the same, a rod connected to each of said sleeves, a link connected to each of said rods, a second rod connected to each of said links, and a crank connected to each of said second-named rods for operating the said sleeves.
8. In an internal combustion engine, the combination of a valve sleeve, a piston moving in the same, an actuating rod connected to said valve sleeve, a slotted link secured to said rod, a member passing through the slot in said link to permit the said link to slide and rock thereon, and means for actuating said slotted link.
9. In an internal combustion engine, the combination of a crank shaft, pistons connected thereto, a plurality of valve sleeves in which said pistons move, a bar parallel to said crank shaft, slotted links mounted upon said bar, actuating rods connecting one of said slotted links to each of said valve sleeves, and means for operating said links to move the valve sleeves in a manner required in the course of the operation of the engine.
10. In an internal combustion engine, the combination of a crank shaft, a second crank shaft parallel therewith and connected thereto to operate at half the speed thereof, a bar parallel with said crank shaft, means for forming a plurality of power chambers each comprising a valve sleeve, a piston moving in each of said valve sleeves, a plurality of slotted links mounted upon the said bar to rock and slide thereon, a rod for connecting each of said links to one of said valve sleeves, and another rod for connecting each of said links to the second crank shaft to operate the said valve sleeves.
11. In an internal combustion engine, the combination of a casing, a head for said casing having an internal projection, a ring carried by said casing having ports extending therethrough and through the wall of said casing, the said ring being of greater diameter than said internal projection of the head and surrounding the same at its inner end, a valve sleeve passing through said ring and receiving the internal projection of said head, the other end of said casing having an opening through which said valve sleeve passes, and means for operating the valve sleeve, said sleeve being separated from the wall of the casing to form a space for the circulation of a cooling and lubricating agent in contact with the sides and ends of said valve sleeve.
12. In an internal combustion engine, the combination of a casing having a head with an internal projection, a ring carried inside of said casing and of larger diameter than said head, said ring having ports extending through the same, said casing having ports corresponding with said first-named ports, and a pair of concentric valve sleeves passing through said ring and said head, the other end of said casing having an opening through which said sleeves pass, said sleeves being spaced from the wall of said casing to provide for the circulation of cooling and lubricating fluid in contact with the sides and ends of said sleeves.
13. In an internal combustion engine, a casing having intake and exhaust ports, a cylindrical head projecting into the same

- and having a returned flange, the head being provided with a space extended down between the inner wall of the head and the said flange, a pair of telescoping cylindrical sleeves received in said casing, said sleeves having ports adapted to register with said intake and exhaust ports, a working piston received by the inner of said sleeves, said head, said sleeves and said piston forming a power chamber, and means driven by said piston for reciprocating said sleeves, said sleeves being separated from said casing to form a space for a lubricating and cooling agent, the said space communicating with 15 the space in the head.
14. In an internal combustion engine, the combination of a casing having intake and exhaust ports, a head having a projection extending into the casing, a cylindrical sleeve valve inside of said casing having ports to register with said intake and exhaust ports, the said sleeve valve receiving the projection of the said head, said sleeve valve being separated from the wall of the 20 casing to form a space to receive a lubricating and cooling agent, a web for closing the bottom of said space and having an opening for the passage of the sleeve valve and an upwardly extending flange surrounding said 25 opening and engaging the outer surface of said valve, a working piston moving in said sleeve valve, and means driven by said piston for reciprocating said sleeve valve.
15. In an internal combustion engine, the combination of a casing and a pair of reciprocating sleeve valves having intake and exhaust ports, said valves telescoping one within the other and being separated from the wall of said casing to form a space 30 for receiving a lubricating and cooling agent, a head having a projection extending into the inner sleeve valve and provided with packing rings engaging the inner surface of said inner sleeve valve, the said head having a space communicating with the said 35 space between the wall of the casing and the sleeve valves, said casing having a web opposite said head for closing the corresponding end of the space for the cooling 40 and lubricating agent, the said web having 45
- 50

an opening for the passage of the sleeve valves, and a flange surrounding said opening and provided with packing rings engaging the outer surface of the outer sleeve valve.

16. In an internal combustion engine, the combination of a casing having an internal ring, a passage leading through the wall of said casing and said ring, said casing having a head coaxial with said ring and projecting into the same but of less diameter, said casing also having an opening opposite said head of the same diameter as the ring, and a sleeve valve having a port to register with the passage passing through 60 said opening and said ring and received by said ring, said ring having packing means adjacent the ports, and said head and said casing adjacent said opening likewise having packing rings to engage the sleeve valve, 65 said valve being separated from the wall of the casing to form a space for a lubricating and cooling agent.

17. In an internal combustion engine the combination of a crank case, a casing 70 mounted thereon having an internal ring at its upper end provided with ports extending therethrough and through the wall of the casing, said ring formed integral with the casing and forming a guide for the inner 75 end of a reciprocating tubular valve having ports, said ring surrounding the valve and so fitted thereto that the ports of the valve have lapping contact with said ring and the ports of the cylinder, the latter ports 80 registering respectively with the corresponding tubular valve ports during suction and exhaust strokes of the piston, and a head 85 for said casing having a projection extending into the casing and spaced from the said 90 ring for the passage of the said tubular valve.

In testimony whereof I have signed my name to this specification in the presence of two subscribing witnesses.

JAMES KEISTER.
